United States Patent [19]

Datta et al.

[11] Patent Number: Des. 311,437

[45] Date of Patent: ** Oct. 16, 1990

[54] GAS PRESSURE REGULATOR

[75] Inventors: Bishnu P. Datta; David G. Anderson, both of Florence, S.C.

[73] Assignee: L-TEC, Florence, S.C.

[**] Term: 14 Years

[21] Appl. No.: 182,589

[22] Filed: Apr. 18, 1988

[52] U.S. Cl. D23/233; D10/49; D10/85

CLAIM

The ornamental design for a gas pressure regulator, as shown.

DESCRIPTION

FIG. 1 is a front elevational view of a gas pressure regulator embodying our new design;

FIG. 2 is a rear elevational view;

FIG. 3 is a left side elevational, the right side elevational view being a mirror image;

FIG. 4 is a top plan view;

FIG. 5 is a front elevational view of another embodiment of FIGS. 1-4;

FIG. 6 is a rear elevational view;

FIG. 7 is a left side elevational view, the right side elevational view; and

FIG. 8 is a top plan view thereof.

Fig. 1.

Fig. 2.

Fig. 3.

Fig. 4.

FIG. 5.

FIG. 6.

FIG. 8.

FIG. 7.
